STOPPER DEVICE FOR DRAIN OUTLETS

Reuben Rabinovich, Chicago, Ill.

Application October 27, 1933, Serial No. 695,490

16 Claims. (Cl. 4—287)

The present invention relates to improvements in stopper devices for drain outlets, and has for its primary object the provision of a novel stopper device adapted to open automatically when the liquid level exceeds a predetermined height.

Other objects are to provide a new and improved stopper device of the foregoing character which can also be actuated manually to open the drain outlet, which is simple and inexpensive in construction, and which is sensitive and reliable in operation.

A further object resides in the provision of a novel strainer adapted to be positioned over the stopper device without interfering with the manual or automatic operation of the latter.

Other objects and advantages will become apparent as the description proceeds.

In the accompanying drawing, Fig. 1 is a vertical sectional view, taken along line 1—1 of Fig. 2 of a stopper device embodying the features of my invention.

Figs. 2 and 3 are transverse sectional views taken respectively along lines 2—2 and 3—3 of Fig. 1.

Referring more particularly to the drawing, the invention resides in an automatic stopper device for closing the waste or drain outlets of various kinds of plumbing fixtures, such for example as bath tubs, wash basins, laundry tubs, sinks, lavatories and other similar receptacles. The stopper device is adapted to open the drain outlet of the receptacle when the level of the water or liquid therein reaches a predetermined height, and hence renders unnecessary the overflow opening which is commonly provided. Overflow openings are undesirable from the standpoint that they become unsanitary, and involve extra manufacturing expense and difficulties. The present automatic stopper device is adapted to occupy either a fully closed position in which it seals the drain outlet, or a fully open position in which it permits the liquid to drain completely from the receptacle, and therefore operates in the dual capacity of a normal plug, or a safety device for preventing the liquid from overflowing the receptacle when, through lack of attention, the level rises too high. For purposes of illustration, the stopper device is shown in operative relation to a drain outlet 10 in a wall 11 adapted to constitute the bottom of any suitable receptacle of the foregoing character.

Within the broad aspects of the invention, the stopper device comprises a diaphragm 12 of water impervious resilient material, such as rubber, which is formed with a central opening 13

adapted to be closed from the underside by a stopper 14, and which is adapted to close the outlet 10 when the stopper is in closed position. The diaphragm 12 is adapted to be mounted in any suitable position in relation to the drain outlet 10, for example in a drain passage 15 leading downwardly from the outlet, so that its upper surface is adapted to be acted upon through the outlet by the hydraulic head of whatever liquid may be present in the receptacle. The peripheral margin of the central opening 13 is adapted to snugly and yieldably embrace the periphery of the stopper 14, and to interlock therewith so as to retain the latter in closed position under normal conditions. However, when the liquid head exceeds the desired maximum, it acts to deflect the diaphragm 12 downwardly out of its normal flat horizontal plane, thereby expanding the opening 13 to release the stopper 14.

The interlocking engagement between the diaphragm 12 and the stopper 14 may be accomplished in any suitable manner. In the present instance, the stopper 14 is slightly conical upwardly, and is formed adjacent its large end with a peripheral generally V-shaped groove 16. The inner peripheral margin of the opening 13 is formed with an annular inwardly protruding lip 17 adapted when contracted to tightly engage in the groove 16. Rising from the upper surface of the diaphragm 12 about the lip 17 is a conical collar 18 constituting a seat adapted to receive and peripherally embrace the stopper 14 above the groove 16. Preferably, an inner peripheral flange 19 is formed on the upper end of the collar 18.

In the preferred form of the stopper device, the diaphragm 12 is mounted in a fixed horizontal position within a special self-draining vessel 20 which defines the drain passage 15. The upper end portion of the vessel 20 extends through the drain outlet 10, and is flared outwardly as indicated at 21 to seat against the top of the wall 11. A nut 22 threaded onto the vessel 20 and against the underside of the wall 11 serves to hold the vessel securely in position. The lower end of the vessel 20 is reduced in size for connection with a pipe (not shown).

The diaphragm 12 may be provided in any suitable shape, and in the present instance is in the form of a circular disk conforming closely to the interior of the vessel 20, and having an upstanding outer peripheral rim 23. A metal case or ring 24 is forced tightly about the rim 23, and is threaded downwardly on the interior of the vessel 20 against an annular flange 25 to support

the diaphragm 12 rigidly in position with a tight seal at the outer periphery.

Preferably, a thin metal ring 26 is embedded in the rim 23 to reinforce the outer edge of the diaphragm 12. Similarly, a light metal ring 27 is embedded in the upper end of the collar 18 to retain the shape of the opening 13.

The stopper 14 may be provided in any suitable form adapted to interfit with the opening 13. In 10 the present instance, the stopper 14 comprises a circular bottom plate 28 adapted to engage against the underside of the diaphragm 12, thereby arresting upward movement of the stopper, an annular concentric wall 29 formed on the top 15 of the plate within the outer periphery, and an upper end plate 30 formed with a depending peripheral flange 31 encircling the upstanding wall. Preferably, the exterior of the flange 31 is tapered upwardly to impart a conical shape to 20 the stopper 14, and the top of the plate 30 is rounded or globular so that solid matter will not lodge thereon.

The lower edge surface of the flange 31 is flared upwardly and outwardly, and is spaced 25 from the plate 28. Thus, the plate 28 and the flange 31 define the annular groove 16. To provide for adjustment of the width and internal diameter of the groove 16, so as to obtain and retain a close fit with the lip 17, the end plates 30 30 and 30 are axially adjustable relatively to each other. In the present instance, the sleeve 31 telescopes slidably with the wall 29, and the end plates 28 and 30 are urged apart by a coiled compression spring 32 interposed therebetween. Extending axially through the end plates 28 and 30 35 of the stopper 14 and through the spring 32 is a vertical stem 33. The lower end of the stem 33 is enlarged and square in cross-section to engage the underside of the bottom plate 28, and the 40 upper end is threaded to receive an adjusting nut 34. Positioned on the stem 33 between the top plate 30 and the nut 34 is a spacer sleeve 35. It will be evident that by adjusting the nut 34 and sleeve 35 on the stem 33, the top plate 30 45 will be depressed against the action of the spring 32 to contract the groove 16, or will be permitted to rise under the influence of the spring to expand the groove.

The stopper 14 has a fully closed position and a 50 fully open position, and in use occupies one or the other. Preferably, the open position is defined by a vertical sleeve 36 which rises from the center of two perpendicular diametrical cross pieces 37 rigidly fixed in the reduced lower end of the vessel 20, and which is adapted to be engaged at the 55 upper end by the underside of the plate 28. The sleeve 36 also serves to guide the stopper 14 in its movements, and to this end is made square in cross-section to slidably receive the squared lower 60 end of the stem 33.

Any suitable means that is conveniently accessible may be provided for adjusting the stopper 14 into closed position. In the present instance, this means consists of the stem 33, the upper end 65 of which is provided with a hand grip 38 accessible through the drain outlet 10.

By reason of the square sleeve 36, the nut 34 may be turned on the stem 33 without removing the stopper 14 from the vessel 20 to adjust the 70 stopper for automatic release at various liquid heights.

Removably positioned in the upper end of the vessel 20 is a cup shaped strainer 39, formed with a large number of small closely spaced apertures 75 40, which is adapted to permit the free passage

of liquid through the drain outlet 10, but not coarse refuse or other solid matter. The upper end of the strainer 39 is flared outwardly, as indicated at 41, to seat against the flared upper end 21 of the vessel 20. The upper end of the stem 33 extends in freely spaced relation through an upstanding sleeve 42 formed integral with the center of the bottom of the strainer 39. Hence, the stem 33 can be actuated without removing the strainer 39, and the strainer can be removed without disturbing the stem or stopper.

The operation of the stopper device will be evident from the foregoing description, and briefly summarized is as follows: To close the drain outlet 10, the hand grip 38 is lifted to force the stopper 14 into the collar 18 until the lip 17 engages in the groove 16. The upper edge of the collar 18 and the flange 19, being stiffened by the metal ring 27, prevents the stopper 14 from being pulled upwardly through the diaphragm 12. The resulting interlock acts to retain the stopper 14 in closed position against the weight of any normal amount of liquid in the receptacle. However, if the level of the liquid should rise above a predetermined maximum, the resulting pressure will flux the central portion of the diaphragm 12 downwardly, and thereby expand the lip 17 sufficiently to release the stopper 14. Because of the metal ring 27, the opening 13 enlarges mostly at the bottom. Thereupon, the stopper 14 will be moved automatically into its open position against the sleeve 36. The maximum permissible liquid level may be varied by adjusting the width of the groove 16. It will be understood that the drain passage 15 can be opened at any time by manually depressing the stem 33.

The stopper device is reliable and accurate in operation, and is simple, inexpensive and durable in construction. The diaphragm 12 is conveniently accessible through the drain outlet 10, and therefore can be easily and quickly replaced when desired. While I have illustrated and described one embodiment of the invention, it is to be understood that various changes and modifications may be made without departing from the spirit and scope of the invention as expressed in the appended claims.

I claim as my invention:

1. In a stopper device, in combination, a normally flat circular resilient diaphragm adapted to be fastened in a fixed position about its periphery, and having a central portion formed with an opening and adapted to be flexed out of the plane of said periphery when subjected to pressure, and a stopper adapted to be removably inserted from one side of said diaphragm into said opening to close the latter, said diaphragm when relaxed tightly and yieldably embracing said stopper to retain said stopper in said opening, and when flexed to a predetermined degree acting to expand said opening to release said stopper.

2. In a stopper device, in combination, a resilient diaphragm adapted to be fastened in a fixed position about its perimeter, and having a central portion formed with an opening and adapted to be flexed when subjected to pressure, and a stopper adapted to be removably inserted into said opening to close the latter, said diaphragm when relaxed yieldably embracing said stopper and when flexed to a predetermined degree acting to expand said opening to release said stopper.

3. In a stopper device, in combination, a resilient diaphragm adapted to be fastened in a fixed

- position about its perimeter, and having a central portion formed with an opening and adapted to be flexed when subjected to pressure, an annular sleeve integral with one side of said diaphragm closely about said opening, the peripheral margin of said opening defining an annular lip projecting inwardly from said sleeve, and a stopper formed with a peripheral groove and adapted to be removably inserted from the other side of said diaphragm into said sleeve with said lip engaging in said groove to close said opening, said diaphragm when relaxed tightly embracing said stopper and when flexed toward said other side to a predetermined degree acting to expand said lip to release said stopper.
4. In a stopper device, in combination, a resilient diaphragm adapted to be fastened in a fixed position about its perimeter, and having a central portion formed with an opening and adapted to be flexed when subjected to pressure, and a stopper adapted to be removably inserted into said opening to close the latter, said diaphragm and said stopper having parts in yieldable interlocking engagement to hold said stopper in said opening, said diaphragm when relaxed tightly embracing said stopper and when flexed to a predetermined degree acting to expand said opening and to disengage said parts to release said stopper.
5. In a stopper device, in combination, a circular resilient diaphragm adapted to be fastened in a fixed position about its outer periphery, and having a central portion formed with an opening and adapted to be flexed when subjected to pressure, an annular sleeve integral with one side of said diaphragm closely about said opening, the peripheral margin of said opening defining an annular lip projecting inwardly from said sleeve, an annular reinforcing member embedded in the free end of said sleeve, and a stopper formed with a peripheral shoulder, and adapted to be removably inserted into said sleeve with said shoulder in interlocking engagement with said lip to close said opening, said diaphragm when relaxed tightly embracing said stopper and when flexed to a predetermined degree acting to expand said lip out of engagement with said shoulder to release said stopper for movement out of said sleeve.
6. A stopper device for a drain outlet comprising, in combination, a self draining vessel adapted to open downwardly from said outlet, a diaphragm of resilient material mounted in said vessel to close the passage therethrough and having a central opening formed with an upstanding peripheral sleeve and a peripheral lip projecting inwardly from the lower edge of said sleeve, a stopper movable from an open position upwardly into said sleeve to close said opening and having a peripheral groove adapted to receive said lip, means for supporting said stopper in said open position and for guiding said stopper in its vertical movements, and means for raising said stopper into closed position.
7. A stopper device for a drain outlet comprising, in combination, a horizontal diaphragm of resilient material mounted in said outlet to close the passage therethrough and having a central opening formed with an upstanding peripheral sleeve and an annular lip projecting inwardly from the lower edge of said sleeve, a stopper movable from an open position upwardly into said sleeve to close said opening and having a peripheral groove adapted to receive said lip, means for supporting said stopper in said open position, and an axial stem on said stopper extending upwardly through said opening for manual actuation to lift said stopper into closed position.
8. A stopper device for a drain outlet comprising, in combination, a diaphragm of resilient material mounted in said outlet to close the passage therethrough and having a central opening, a stopper movable from an open position upwardly into said opening, said diaphragm and said stopper having parts movable into yieldable interlocking engagement to hold said stopper in said opening, means for supporting said stopper in said open position, a perforated strainer mounted in said outlet over said diaphragm and having an open axial sleeve, and a stem on said stopper extending upwardly through said opening and said sleeve.
9. A stopper device for a downwardly opening drain outlet comprising, in combination, a valve in said outlet, a strainer removably seated in said outlet above said valve and having an intermediate opening, and a stem for operating said valve, said stem extending upwardly through said opening.
10. In a stopper device, in combination, a resilient diaphragm adapted to be fastened in a fixed position about its perimeter, and having a central portion formed with an opening and adapted to be flexed when subjected to pressure, the inner peripheral margin of said opening defining an annular lip, and a stopper movable into said opening, said stopper having two relatively axially adjustable parts defining an annular groove adapted to interlock with said lip.
11. In a stopper device, in combination, a resilient diaphragm adapted to be fastened in a fixed position about its perimeter, and having a central portion formed with an opening and adapted to be flexed when subjected to pressure, the inner peripheral margin of said opening defining an annular lip, and a stopper movable into said opening, said stopper having two end members with telescoping flanges and defining an annular groove adapted to receive and interlock with said lip, spring means tending to separate said members, and adjustable means for defining the position of said members and the width of said groove.
12. In a stopper device, a flexible diaphragm of resilient material adapted to be fastened at its perimeter in a fixed position and having a central portion formed with an opening adapted to receive a stopper, said central portion when relaxed being adapted to yieldably embrace said stopper to hold the latter in position, and when flexed under pressure acting to expand said opening to release said stopper.
13. In a stopper device, a flexible normally flat circular diaphragm of resilient material adapted to be fastened at its periphery in a fixed position and having a central portion formed with an opening, a sleeve integral with one side of said diaphragm, the peripheral margin of said opening defining an annular lip projecting inwardly from said sleeve, said sleeve and lip being adapted to receive a stopper with a shoulder on the latter in interlocking engagement with said lip, said central portion when flexed acting to expand said lip to release said stopper.
14. A stopper device for a drain outlet comprising, in combination, a self draining vessel adapted to open downwardly from said outlet, a diaphragm of resilient material mounted in said vessel to close the passage therethrough and having a central opening, a stopper movable from an open position upwardly into said opening, a

- vertical non-circular guide sleeve fixed in said vessel below said diaphragm, and a vertical stem projecting axially from opposite sides of said stopper respectively through said opening and into said sleeve.
15. A stopper device for a downwardly opening drain outlet, a horizontal partition mounted across said outlet and having an opening defining a resilient valve seat, a stopper movable from below said partition upwardly into said opening for yieldable peripheral engagement by said seat, said seat being operable normally to retain said stopper in position, and to release said stopper
16. In a stopper device for a downwardly opening drain outlet in which a valve with a vertical actuating stem is adapted to be mounted, a perforated cup-shaped strainer adapted to be removably mounted in said outlet over said valve, and having an open central sleeve rising from its bottom wall through which said stem is adapted to extend freely for actuation from above said strainer. 80 85
